ABSTRACT

A noise reduction circuit has a transistor and impedance elements coupled to its emitter and collector respectively and an input signal applied to its base. The impedance of the collector impedance element is a function both the amplitude and frequency of the input signal. It can be another transistor and a variable bandpass filter. A switch can be part of the circuit so that it can be used during both recording and reproducing.

NOISE REDUCTION CIRCUIT

BACKGROUND OF THE INVENTION

The present invention relates to a circuit that has a transfer function that is a function of both the amplitude and frequency of the input signal, and more particularly, to one that can be used during both magnetic recording and reproducing to reduce noise.

In magnetic recording, a signal, which can correspond to audio, video or other information is applied to a magnetic head which magnetizes areas of an adjacent moving magnetic record in accordance with the frequency and amplitude of the applied signal. During reproduction, the record moves past the head, inducing an electrical signal therein, which is a substantial reproduction of the original signal. Unfortunately, the record also introduces noise into the reproduced signal, which is highly annoying to a listener or an observer.

This noise is however non-uniformly distributed with respect to frequency, which allows a compressor-expander type noise reduction circuit to be used. This circuit has a transfer function such that signals having a small amplitude and a frequency in the vicinity of the frequency of the noise introduced by the record are boosted. As a result, the signal-to-noise ratio of the signal recorded on the magnetic record carrier will be increased, and the information signal will be distorted because of this frequency-dependent and amplitude-dependent transfer function. When the signal is played back this distortion must obviously be eliminated, and therefore the output signal from the reproducing head is applied to an expander circuit which has a transfer function which is complementary to that of the compressor circuit. Consequently the original signal is obtained in the undistorted condition. However, the noise which is caused by the record and the information signals which have a corresponding frequency and originally had a small amplitude will be particularly reduced, so that the improved signal-to-noise ratio of the signal is retained during playback.

Obviously, to achieve distortion free playback of the signal it is of particular importance that the transfer functions of the two signal transmission devices, the compressor and the expander, are complementary to one another as exactly as possible. The stringency of this requirement increases with an increase in complexity of the transfer function of the compressor and expander with respect to dependence upon amplitude and frequency. A high degree of complexity usually is desirable to obtain effective noise reduction, but this will cause the required circuits to be more critical and possibly cause instabilities in any feedback loops used to obtain the transfer function.

It is therefore an object of the present invention to provide a circuit having a transfer function that varies with both frequency and amplitude.

It is another object to provide a noise reduction circuit.

It is yet another object to provide a single unit noise reduction circuit that can be used for both compression and expansion so as to obtain exactly complementary transfer functions.

It is a further object to provide such a circuit that can be made by integrated circuit techniques.

It is yet a further object to provide such a circuit that is stable.

SUMMARY

In brief, these and other objects are achieved by a circuit having a controlled source which includes a control and main conduction electrodes. An input signal is applied to said control electrode. An amplitude and frequency varying impedance element is coupled to one of said conduction electrodes and another impedance element is coupled to the other conduction electrode. An output signal is derived from one of said impedance elements. The circuit therefore has a transfer function that varies with both frequency and amplitude, and hence can be used as a compressor or expander for noise reduction. A switching means can be added to change the locations to which the input signal is applied and from which the output signal is derived so that the circuit can be used as both a compressor and an expander. Hence the transfer functions will be identical and the circuit will be small and suitable for manufacture as an integrated circuit.

Other objects, advantages, and features will become apparent from the description when taken in conjunction with the accompanying drawings in which:

FIG. 1 shows a first embodiment of the transmission device according to the invention,

FIG. 2 shows an embodiment having the same structure but a second impedance element of different design,

FIGS. 3 and 4 show two embodiments which each have a transfer function complementary to that of the device shown in FIG. 2,

FIG. 5 shows a combined circuit by means of which two mutually complementary transfer functions are obtainable,

FIG. 6 shows a more elaborate structure of the network in a preferred embodiment of the invention,

FIG. 7 shows an embodiment largely suitable to be manufactured in integrated circuit form, and

FIGS. 8 and 9 illustrate the frequency-dependent and amplitude-dependent behaviour of this embodiment.

In the Figures corresponding elements are designated by like reference symbols.

The signal transmission device shown in FIG. 1 comprises a transistor T_1 of the npn-type. The emitter of this transistor T_1 is connected to the negative terminal of the supply source, for example to ground, via a first impedance element Z_1 . The collector of the transistor T_1 is connected to the positive terminal $+V_B$ of the supply source via a second impedance element Z_2 . The input signal V_i is applied to the base of the transistor T_1 and the output signal V_o is derived from the collector of the transistor T_1 .

The impedance of element Z_2 is a function of both amplitude and frequency because it comprises the parallel combination of an inductance L , a resistor R and two diodes D and D' connected in inverse parallel. The impedance element Z_2 further comprises an impedance Z_3 connected in series with the said parallel combination. This design of the impedance element Z_2 may be used, for example in a system for the reduction of noise in a video signal, in which use the non-linear distortion produced by this design will in general be permissible.

For audio uses, in which this distortion will in general not be permissible, the impedance element Z_2 may have a structure as shown in FIG. 2. In the embodiment shown in this FIG. the impedance element Z_2 comprises

an impedance Z_4 , the collector emitter path of a transistor T_2 of the npn-type, and an impedance Z_3 , which are connected in series between the terminal $+V_B$ and the collector of the transistor T_1 . The impedance element Z_2 further comprises a network G which receives a signal from the impedance Z_4 and applies a first control signal derived from this signal to the base of the transistor T_2 . The structure of the signal transmission device shown in FIGS. 1 and 2 has the advantage that it enables the complementary transfer function to be simply realized with the use of the same impedance element Z_2 . This will be proved by calculating the transfer function of the device shown in FIG. 2.

Neglecting the base-emitter voltage of the transistor T_1 and the output current, the signal current in the series circuit comprising the impedances Z_1 , Z_3 , Z_4 and the main current paths of the transistors T_1 and T_2 will be equal to V_i/Z_1 . On the basis of this signal current the control voltage applied to the base of the transistor T_2 is $-(Z_4g/Z_1)V_i$, where g is the transfer function of the network G . Neglecting the base-emitter voltage of the transistor T_2 , the emitter voltage has the same value and the output signal V_o is:

$$V_o = -(Z_3 + gZ_4/Z_1)V_i \quad (1)$$

This expression shows that the frequency-dependent and amplitude-dependent nature of the transfer function is determined by the impedances Z_1 , Z_3 and Z_4 and also by the transfer function g of the network G . Hence, the impedances Z_1 , Z_2 and Z_3 may be in the form of resistors, while the variations of the transfer functions are mainly determined by the network G . However, as an alternative, one or more of the impedances Z_1 , Z_2 and Z_3 may be made frequency-dependent and, if desired, amplitude-dependent. The impedance Z_3 may even be entirely dispensed with. If comparatively complex transfer functions are to be synthesized, it will in general be preferable for the frequency dependence and the amplitude dependence to be largely determined by the network G .

As has been mentioned hereinbefore, it is highly desirable that in achieving the complementary transfer function the same elements can be used, in particular the elements which primarily determine the transfer function, i.e. the impedances Z_1 , Z_3 , Z_4 and the network G . Because of the choice of the design of the signal transmission device this may simply effected in a variety of manners, two examples being shown in FIGS. 3 and 4.

The embodiment shown in FIG. 3 substantially corresponds to the device shown in FIG. 2. The single difference from the circuit shown in FIG. 2 consists in that the transistor T_1 of the npn-type has been replaced by a transistor T_3 of the pnp-type, which naturally entails that the collector and emitter connections have changed positions. In this embodiment, the input signal V_i is applied to the base of this transistor and the output signal V_o is derived from its collector, which here is connected to the impedance Z_1 . A simple calculation shows that the relationship between the input signal and the output signal for this device is given by

$$V_o = -(Z_1/Z_3 + g Z_4) V_i \quad (2)$$

which relationship obviously is fully complementary to the transfer function of the device shown in FIG. 2. If an impedance element Z_2 is used which corresponds to the element Z_2 shown in FIG. 1, the device shown in FIG. 3 will obviously have a transfer function which is complementary to that realized by the device shown in FIG. 1.

For a noise reduction system for use in a tape recorder in which during recording, the signal is to be compressed, and during playback the signal is to be expanded, this means that the same impedance elements Z_1 and Z_2 may be used for both modes and that the desired mode may be selected by switching either a transistor T_1 (FIG. 2) or a transistor T_3 (FIG. 3) into circuit.

A transfer function complementary to that of the device shown in FIG. 2 may also be obtained by connecting the impedance element Z_2 in the emitter circuit and the impedance element Z_1 in the collector circuit and replacing the npn-transistor T_2 by a pnp-transistor. This circuit has the disadvantage that the impedance element Z_2 is changed.

FIG. 4 shows a third circuit for achieving a complementary transfer function. This circuit also comprises an impedance element Z_2 , a first terminal of which here is also connected to the positive terminal $+V_B$ of the supply source. However, the second terminal is connected to ground via a current source I and to the emitter of a transistor T_5 of the npn-type. To the base of transistor T_5 , the input signal V_i is applied. The collector of the transistor T_5 is connected to the positive terminal of the supply source via the impedance Z_1 . From impedance Z_1 , the output signal V_o is derived.

The impedance Z_1 , the transistor T_5 and the impedance element Z_2 here also form a series circuit with respect to the signal current, because the current source I supplies a constant current. Again the formula (2) is simply found for the transfer function. The advantage of the device shown in FIG. 4 is that only transistors of the npn-type are used, the moreover this device may advantageously and simply be combined with the device shown in FIG. 2, as is illustrated in FIG. 5.

The device shown in this Figure again comprises the impedance element Z_2 , which is connected in series with the collector emitter path of the transistor T_1 and the impedance Z_1 between the positive terminal $+V_B$ and ground. The device further comprises a transistor T_5 the emitter of which is connected to the collector of the transistor T_1 . A switch S_2 enables the input signal V_i to be selectively applied to the base of the transistor T_1 or to the base of the transistor T_5 , while a switch S_4 enables the output signal V_o to be selectively derived from the collector of the transistor T_1 or from the collector of the transistor T_5 . The said switches S_2 and S_3 are ganged with one another, so that all the switches S_1 and S_4 occupy either the positions designated by a or the positions designated by b . When in the position b the switch S_1 connects the collector of the transistor T_5 to one terminal of the impedance Z'_1 . The other terminal of impedance Z'_1 is connected to the positive terminal $+V_B$ of the supply source. The switch S_3 when in the position b connects the base of the transistor T_1 to a reference voltage V_R .

It will be clear that when the switches S_1 to S_4 are in the position a the operative part of the device is identical to the device shown in FIG. 2. When the switches

are in the position *b*, a fixed reference voltage V_R is applied to the base of the transistor T_1 . This means that the collector current of the transistor T_1 then is constant and consequently this transistor acts as a current source. Hence it will readily be appreciated that in this case the operative part of the device is identical to the device shown in FIG. 4. If the two transfer functions are required to be complementary, the only requirement to be satisfied is that the impedances Z'_1 and Z_1 are equal. Therefore these impedances may expediently be resistors, because resistors may simply be made exactly equal, so that the frequency-dependent and amplitude-dependent characteristic is primarily determined by the impedance element Z_2 . Thus, changing over the switches S_1 to S_4 , which obviously may take the form of electronic switches, enables a complementary transfer function to be selected, according to whether a signal is recorded or a recorded signal is played back, and this selection also may obviously be performed automatically.

FIG. 6 shows the device of FIG. 2 in which, by way of example, the structure of the network G is shown schematically. This network G includes a filter F_1 , for example a high-pass filter. The output signal of this filter is applied via an amplifier A_1 to the base of the transistor T_2 . The output signal of the amplifier A_1 is also applied to a second amplifier A_2 which may have a frequency-dependent amplification factor. The amplitude of the output signal of the amplifier A_2 is measured by means of a detector D and the measured value is applied to a non-linear filter F_2 which may have a nature which is both frequency-dependent and amplitude-dependent. The output signal of this filter F_2 is applied to a control input of the filter F_1 , the cut-off frequency of which is controllable by means of the signal applied to this control input. Alternatively, the amplifier A_1 may be controllable, its amplification factor depending upon the signal applied to its control input, which is indicated by a broken line. This schematically shown structure of the network G enables a wide variety of transfer functions to be realized in accordance with the instantaneous purpose.

FIG. 7 shows an embodiment of a device as shown in FIG. 6 which is highly suitable for manufacture in integrated-circuit form and is particularly suited for use in audio tape recorders, and FIGS. 8 and 9 show characteristics of this device.

In FIG. 7 the elements of the network G as shown in FIG. 6 are enclosed in broken-line boxes. The device as shown in FIG. 7 includes a transistor T_1 to the base of which the input signal V_i is applied and from the collector of which the output signal V_o is derived. The impedances Z_1 , Z_3 and Z_4 in the series circuit between ground potential and the positive terminal $+V_B$ of the supply source are constituted by resistors R_1 , R_2 and R_3 . This series circuit further comprises the collector emitter path of the transistor T_2 connected between the resistors R_3 and R_2 .

The signal voltage produced across the resistance R_3 is applied to an emitter follower circuit which comprises a transistor T_3 and a resistor R_4 and forms part of a high-pass filter F_1 . The filter action is obtained by means of an RC network comprising a capacitor C_1 and a resistor R_5 . The filter F_1 further comprises a transistor T_4 in inverse connection, the collector emitter path of which shunts the resistor R_5 and to the base of which a control signal is applied. The impedance introduced

by this transistor in parallel to the resistor R_5 obviously influences the RC time constant, and hence the cut-off frequency of the filter (C_1 , R_5 , T_4), so that this cut-off frequency depends upon the control signal applied to the base of the transistor T_4 .

The output signal of this high-pass filter F_1 is applied to an amplifier A_1 . This amplifier A_1 includes a differential stage which comprises transistors T_5 and T_6 emitter impedances R_6 and R_7 and a common emitter impedance R_8 . The output signal of the filter F_1 is applied to the base of the transistor T_5 , and to the base of the transistor T_6 there is applied a reference voltage which is obtained by means of a voltage divider R_{12} , R_{13} and an emitter follower circuit comprising a transistor T_7 and a resistor R_{11} . The differential pair T_5 and T_6 may be biased so as to provide a desired amplitude limitation of the signal. The resistor R_{11} is also connected to the resistor R_5 . A voltage divider R_9 and R_{10} is connected in the collector circuit of the transistor T_6 . From the tap on this voltage divider an output signal is derived which is applied to a voltage divider R_{24} , R_{25} the tap on which is connected to the transistor T_2 .

A second output signal of the amplifier A_1 is derived from the collector of the transistor T_6 and applied to an amplifier A_2 . This amplifier A_2 has a frequency-dependent amplification factor, because the parallel combination of a resistor R_{15} and a capacitor C_2 is connected via a resistor R_{14} to the emitter of a transistor T_8 of the pnp-type. The output signal of this amplifier A_2 is derived, via a capacitor C_3 , from a collector resistor R_{16} of the transistor T_8 .

The output signal of the amplifier A_2 is applied to the detector D which comprises resistors R_{17} , R_{18} , R_{19} , R_{20} , a capacitor C_4 , and a diode D_1 . The voltage across the capacitor C_4 always is a function of the amplitude of the output signal of the amplifier A_2 . This voltage across the capacitor C_4 is applied to a non-linear filter F_2 .

This filter includes a RC network which comprises a capacitor C_5 and a resistor R_{23} , to which the voltage across the capacitor C_4 is applied. The resistor R_{23} is shunted by diode D_2 connected in the conducting direction, so that the transfer function of this RC network is not only frequency-dependent but also amplitude-dependent. The tap on this RC network is connected to the base of a transistor T_9 of the pnp-type in the emitter lead of which are connected a resistor R_{21} and a diode D_3 which are shunted by a resistor R_{22} . The output signal of this filter F_2 , in this case the collector current of the transistor T_9 , is applied to the control input of the filter F_1 , in this case the base of the transistor T_4 , and thus controls the cut-off frequency of the high-pass filter F_1 .

The transfer function produced by this device, which function consequently has a nature which is both frequency-dependent and amplitude-dependent, is shown in FIGS. 8 and 9. FIG. 8 shows on a logarithmic scale the voltage V_u at the base of the transistor T_2 as a function of the amplitude of the input signal V_i for three frequencies of this input signal, where $f_1 < f_2 < f_3$. FIG. 9 shows on a logarithmic scale the output signal V_o as a function of the frequency for three values of the amplitude of the input signal, where $V_{i3} > V_{i2} > V_{i1}$.

Obviously the circuit arrangement shown in FIG. 7 may be varied in many ways, thus enabling the transfer function achieved by the device to be matched to a par-

ticular requirement, without departing from the scope of the invention.

Furthermore, by way of example, the structure of the impedance element Z_2 which is shown in FIGS. 2, 3, 4 and 5 and in which the main current path of the transistor T_2 is connected in series with the impedance Z_4 may be modified by using a structure in which the main current path of this transistor is connected in parallel with this impedance Z_4 . In this case the transistor T_2 must be of a conductivity type opposite to that of T_1 and have its emitter connected to that terminal of the impedance Z_4 which in turn is connected to the positive terminal $+V_B$ of the supply source. Variation of the control voltage at the base of this transistor naturally varies the impedance of the parallel combination of this transistor and the impedance Z_4 .

Additionally, it will be clear that, although in the embodiments shown only bipolar transistors are used, unipolar transistors or tubes may also be used. It will also be appreciated that although the present invention has been described as having a utility in magnetic recording, it can be used in many information and communication systems for noise suppression.

What is claimed is:

1. A circuit comprising a controlled source having a main conduction path and a control electrode, an input means for receiving an input signal including noise coupled to said control electrode, a series circuit having a signal current flowing therethrough and comprising in succession first impedance means, said conduction path and second impedance means, means for reducing said noise in said input signal comprising said second impedance means having an impedance that is a varying function of both the amplitude and frequency of the signal applied thereto, and an output means coupled to one of said impedance means for supplying an output signal, whereby the transfer function between said input and output means is a function of both the frequency and amplitude of said input signal.

2. A circuit as claimed in claim 1 wherein said second impedance means further comprises an amplitude independent impedance element whereby the total impedance of said second impedance means has an amplitude independent component.

3. A circuit as claimed in claim 1 wherein said second impedance means further comprises a second controlled source having a control electrode and a main current path coupled in said series circuit, and network means coupled to receive said signal current for applying a first control signal to said second source control electrode.

4. A circuit as claimed in claim 3 wherein said network means comprises a control element means for generating a second control signal that is a function of said signal current, and a variable element means having a control input means coupled to said control ele-

ment means to receive said second control signal for varying the transfer function of said variable element means.

5. A circuit as claimed in claim 4 wherein said variable element means comprises a controllable filter.

6. A circuit as claimed in claim 4 wherein said variable element means comprises a controllable amplifier.

7. A circuit as claimed in claim 4 wherein said control element means comprises means for detecting said first control signal to produce said second control signal.

8. A circuit as claimed in claim 4 wherein said network further comprises a non-linear filter coupled between said control element means and said variable element means.

9. A circuit as claimed in claim 1 wherein all members of said series circuit are adapted to be coupled to receive the same supply current.

10. A circuit comprising a first controlled source having a main conduction path and a control electrode, an input means adapted to receive an input signal coupled to said control electrode, a series circuit having a signal current flowing therethrough and comprising in succession first impedance means and said conduction path, second impedance means having an impedance that is a function of the amplitude and frequency of the signal applied to said second impedance means, said second impedance means being parallel coupled to said series circuit, whereby a junction is formed between said first source and said second impedance means, a current source coupled to said junction and an output means coupled to one of said impedance means for supplying an output signal, whereby the transfer function between said input and output means is a function of both the frequency and amplitude of said input signal.

11. A circuit as claimed in claim 10 wherein said current source comprises a second controlled source having a main conduction path coupled in series with a third impedance means having a value equal to that of the first impedance means, and a control electrode; and a reference voltage source coupled to said second controlled source control electrode.

12. A circuit as claimed in claim 11 further comprising switching means having a first position for coupling said input means to said first controlled source control electrode, said output means to said first impedance means, and said reference voltage source to said second controlled source control electrode; and a second position for coupling the input signal to said second controlled source control electrode, said output means to said second impedance means, and for breaking the coupling between said first controlled source and said first impedance means.
